Primary Examiner — Selina Sikder

CLAIM

The ornamental design for a hand controller as shown and described.

DESCRIPTION

FIG. 1 is a top, front and right side perspective view of a first embodiment of a hand controller showing our new design; FIG. 2 is a rear perspective view of FIG. 1; FIG. 3 is another rear perspective view of FIG. 1; FIG. 4 is a front elevational view of FIG. 1; FIG. 5 is a rear elevational view of FIG. 1; FIG. 6 is a left side view of FIG. 1; FIG. 7 is a right side view of FIG. 1; FIG. 8 is a top plan view of FIG. 1; FIG. 9 is a bottom plan view of FIG. 1; FIG. 10 is an enlarged view of portion 10 in FIG. 2; FIG. 11 is a top, front and right side perspective view of a second embodiment of the hand controller; FIG. 12 is a rear perspective view of FIG. 11; FIG. 13 is another rear perspective view of FIG. 11; FIG. 14 is a front elevational view of FIG. 11; FIG. 15 is a rear elevational view of FIG. 11; FIG. 16 is a left side view of FIG. 11; FIG. 17 is a right side view of FIG. 11; FIG. 18 is a top plan view of FIG. 11; FIG. 19 is a bottom plan view of FIG. 11; and, FIG. 20 is an enlarged view of portion 20 in FIG. 12. The evenly dashed broken lines in the drawings illustrate portions of the hand controller which form no part of the claimed design.

The unevenly dashed broken lines illustrate the boundary of the enlarged views and form no part of the claimed design.
